ABSTRACT: The combined fuse clip and terminal strap is a single piece of metal punched in the flat to provide a body portion with arms extending laterally from opposite sides of one end of the body and terminal straps extending laterally from opposite sides of the opposite end of the body. The arms are bent generally normal to the plane of the body to form clips for resiliently clamping onto a fuse received therebetween. The straps are bent about form lines at 45° to the length of the body and 90° to each other so they both lie in face to face juxtaposition with each other and with one strap juxtaposed firmly and resiliently in face to face contact with the face of the body opposite the clip arms. The other strap is juxtaposed firmly against the under face of the first strap. The one of the straps juxtaposed against the body has bosses protruding in the same direction as the clip arms for centering a conducting wire to be connected to the terminal straps. The body and straps have aligned openings through which extends a screw which is in threaded engagement with the body for clamping the combined clip and terminal strap to a supporting base.

ONE-PIECE CLIP AND LOAD SIDE TERMINAL STRAP

This invention relates to a one piece fuse clip and terminal strap to be used on the load side of switches or other electrical devices; for example, with a switch such as disclosed in U.S. Letters Pat. No. 3,240,888 of Rys et al., issued Mar. 15, 1966, entitled Electrical Switch With Interlocking Mechanism. The terminal strap is secured to an electrical connector, preferably of the type shown in U.S. Pat. No. 3,133,781, of Rys et al., issued May 19, 1964, and entitled Electrical Connector, but it can be used with other switches and connectors.

Heretofore, fuse clips and terminal straps have been separately formed and secured in assembled relation with a face portion of the fuse clip juxtaposed on the top face of the strap, and the assembled fuse and strap clamped together and to a molded insulating base by a single screw. Generally in such prior clips, the screw is threaded only into the clip which then acts as a clamp to clamp the terminal strap firmly between the clip and base for forming the electrical connection between the clip and strap and for supporting them on the base. As a result the connection between the clip and strap depends upon the holding power of the screw. In many instances the base on which the clip and strap are mounted shrinks upon aging with the result that the electrical connection between the clip and terminal strap loosens.

In accordance with the present invention, the clip and terminal strap are made in one piece so that loosening of the screw does not in any way affect the electrical connection between the strap and the clip.

Furthermore, a strap and clip made of one piece of sheet metal by punching and bending of the sheet metal in accordance with the present invention is very economical to produce, and is very compact and effective in operation.

Various specific objects and advantages will become apparent from the following description wherein reference is made to the drawing, in which:

FIG. 1 is a top plan view of a clip and strap combination embodying the principles of the present invention;

FIG. 2 is an end elevation of a clip and strap combination as illustrated in FIG. 1;

FIG. 3 is a right side elevation of the clip and strap illustrated in FIGS. 1 and 2, and showing it connected to a terminal connector and to a portion of a supporting base;

FIG. 4 is a top plan view of a blank of sheet metal cut to the proper outline for folding and bending into the combined clip and strap shown in FIGS. 1 through 3; and

FIG. 5 is a left side elevation of the connector used in the present invention, the body being shown in section for clearness in illustration.

Referring to the drawings, the combined clip and terminal strap is shown mounted on a base 1 of insulating material. The clip and strap combination is a one-piece structure formed of a flat sheet of relatively stiff, but slightly resilient metal punched to provide a preselected outline and then folded into final form.

The clip and strap comprise a body 2 having lateral integral arms 3 at the opposite edges, respectively, of one end, and integral terminal straps 5 and 6, respectively, extending laterally from the opposite edges, respectively, of its other end.

The arms 3 are bent and shaped to receive a fuse, indicated at F, therebetween and hold it firmly in clamping relation. If desired, a suitable spring S may be provided to increase the clamping pressure of the arms 3.

The strap 5 is connected at its inner end to the body 2 along a form line 7, and the strap 6 is connected at its inner end to the body 2 along a form line 8. In the final product the straps 5 and 6 are bent along the form lines, respectively, so as to dispose both of them so that part way of their length they are in underlying relation to the body and extending lengthwise thereof, and for the remainder of their length they extend beyond the end of the body opposite to the end portion to which they are connected.

In the form illustrated, the strap 5 is first bent along the form line 7 back under the body 2 so that it lies in firm face to face juxtaposition with the underside of the body 2. The strap 6 is bent along the form line 8 so as to underlie, in firm face to face juxtaposition, the underside of the strap 5. Thus the terminal strap is composed, in effect, of two leaves in firm resilient face to face juxtaposition with each other.

The body 2 is provided with an opening 9 and the straps 5 and 6 are provided with openings 10 and 11, respectively. 10 These openings are in alignment with each other for receiving a screw 12. At least one of the openings is internally threaded complementary to the screw 12. In the form illustrated, the threaded opening is the opening 9 in the body 2. The screw 12 is used to mount the combined clip and terminal strap on one 15 face of the base 1 and draw it firmly thereagainst with the clip arms 3 exposed outwardly from the base 1 for receiving the fuse F in snap-fastening relation therebetween.

At least one of the straps, and preferably the strap 5, has bosses 14 on the face facing in the same direction as the face 20 of the body 2 from which the clip arms 3 extend. The bosses 14 are spaced apart from each other in a direction laterally of the straps for centering therebetween a conductor to be attached to the strap.

The strap 5 also has a widened portion 15 which provides a 25 lug for facilitating connection of the terminal strap to a connector 20, such as illustrated.

The connector 20 comprises generally a U-shaped rigid 30 body of conducting material. The body 2 has spaced arms 21 and 22. The arm 21 is provided with a slot 23 and the arm 22 is provided with a slot 24. These slots are arranged to coat with a clamping element 25, as described in the above U.S. Pat. No. 3,133,781. The clamping element 25 can readily be installed 35 therein and held in place by virtue of the clamping effect of a screw 26 bearing on a conductor disposed between the bosses 14 of the terminal strap 5.

As mentioned, the terminal strap 5 has a lug 15 on one side and the connector 20 is provided with slots 27 and 28, respectively, positioned so that when the straps 5 and 6 are mounted 40 within the connector, the lug 15 is received in either one of the slots 27 and 28 simply by inserting the straps endwise into the end of the connector 20 while the strap is disposed edgewise to the base, or parallel to the arms 21 and 22 of the connector, and then turning the straps 90° about their longitudinal axis to dispose the lug 15 in one of the slots 27 OR 28 and the underside of the strap 6 into firm juxtaposition with the face of the connector 20. This assures the proper positioning of the strap in the connector and prevents accidental endwise withdrawal therefrom.

50 It is apparent from the foregoing description that a very effective one piece fuse clip and terminal strap combination is provided which can be produced economically and has the advantages heretofore set forth.

Having thus described my invention, I claim:

55 1. A one-piece sheet metal fuse clip and terminal strap comprising a body;

clip arms integral with the body and extending from the lateral edges, respectively, of the body at one end of the body and an abrupt angle to one face of the body and spaced apart from each other laterally of the body for receiving therebetween a fuse with its axis extending endwise of the body;

60 a strap at the other end of the body and comprising two strap portions integral with the body at said other end and extending endwise of the body back toward and beyond said one end of the body, one strap portion, part way of its length, having one of its faces in firm face to face juxtaposition with the other face of the body and the other strap portion being in firm face to face juxtaposition with the other face of said one strap portion.

65 2. The structure according to claim 1 wherein the body, arms, and strap are composed of a single sheet of relatively stiff and resilient sheet metal and said strap portions are held in firm face to face juxtaposition by the inherent springiness of 70 the metal.

3

3. The structure according to claim 1 wherein said body and strap portions have aligned holes therein, respectively, for accommodating a connecting screw for connecting the body to a supporting base, and the wall of at least one of the holes being threaded with a thread complementary to the thread of the screw.

4. The structure according to claim 1 wherein said one strap portion has bosses on its said one face spaced endwise of the strap from said one end of the body and protruding in the same direction as the arms.

5 The structure according to claim 1 wherein said body at

4

said other end joins the two strap portions along form lines extending at 90° to each other and each at 45° to the length of the body, so that, by bending the strap portions along said lines, the strap portions lie in said juxtaposed face to face relation.

6. The structure according to claim 1 wherein at least one strap portion has a lug portion spaced from the body and wider than the portions of the strap adjacent to it and providing a lug for facilitating connection of the strap with an electrical connector.
